UNITED STATES PATENT OFFICE.

WILLIAM H. BRODIE, OF BROOKLYN, NEW YORK.

WIRE-CLAMP.

SPECIFICATION forming part of Letters Patent No. 592,949, dated November 2, 1897.

Application filed May 8, 1896. Serial No. 590,709. (No model.)

To all whom it may concern:

Be it known that I, WILLIAM H. BRODIE, a citizen of the United States, residing at Brooklyn, Kings county, New York, have invented 55 certain Improvements in Wire-Clamps, of which the following is a specification.

This invention relates to certain improvements in that class of wire-clamps which are employed for suspending trolley-wires and 10 the like; and the object of the invention is to provide a device of this character of a simple and inexpensive construction which shall be light, strong, and durable, and shall be adapted to hold securely clamped trolley or other 15 wires of different diameters.

The invention contemplates certain novel features of the construction of the device, together with certain combinations and arrangements of the various parts, whereby cer- 20 tain important advantages are attained and the clamp is made simpler, cheaper, and otherwise better adapted and more convenient for use than various other similar devices heretofore employed, all as will be hereinafter 25 set forth.

The novel features of the invention will be carefully defined in the claims.

In order that my invention may be the better understood, I have shown in the accom- 30 panying drawings a wire-clamp embodying my improvements, in which drawings—

Figure 1 is a longitudinal vertical mid-section taken through the clamp, and Fig. 2 is a transverse mid-section taken in the plane in- 35 dicated by the line 2 2 in Fig. 1. Fig. 3 is a transverse section taken through the clamp in the plane of the line 3 3 in Fig. 5. Fig. 4 is a fragmentary plan view showing the central portion of the device with the conical ex- 40 panding nut omitted, and Fig. 5 is a plan view of the complete device.

Referring to the drawings, A and B represent the two parts or sections of the clamp, these sections being of similar construction 45 and each being of an elongated form. The sections or parts A and B are provided on their inner faces with projecting perforated lugs *a* and *b*, respectively, there being three such lugs on each section.

The outer lugs *b* on the section or part B of the clamp are arranged to fit, when the device is assembled, between the outer lugs *a*

on the part or section A, but the inner lugs *a* and *b* on the respective sections are so arranged as to stand somewhat spaced apart 55 when the sections are fitted together, said inner lugs embracing between them the head *c* of a screw *C*, arranged centrally with respect to the clamp.

Through the perforations in the respective 60 lugs *a* and *b* of the parts or sections A and B is arranged to pass a hinging rod or pin *e*, serving to connect the parts or sections of the clamp pivotally together, and the head *c* of the screw *C* is also perforated to permit the 65 passage through it of the said rod or pin *e*, whereby the screw *C* is secured in place. In this way it will be seen the parts or sections A and B being hinged together their lower edges form jaws *a'* and *b'*, adapted to receive 70 and hold the trolley or other wire, and in order to enable said jaws to the better engage and grip the wire grooves or channels are formed on the inner edge surfaces of the jaws, as clearly indicated in the sectional 75 views Figs. 2 and 3. In the drawings the wire is indicated at *x*, and it will be seen that wires of different diameters may be engaged in said grooved jaws and securely held.

The respective parts or sections A and B of 80 the clamp are formed at the upper parts of their central portions with lips *a*² and *b*², which are conical on their inner surfaces being, flared outward from their lower parts to the upper, and said lips are arranged to be engaged by a 85 conical nut or wedging-block *D*, screwing on the upper end of the screw *C*. The nut *D* has, as shown, a hexagonal form to adapt it to be readily engaged by a wrench or the like, and in its upper part said nut is formed with 90 a counterbore *d* to receive the bolt or screw (not shown) by means of which the clamp is to be suspended.

In use the wire *x* to be clamped is inserted between the two jaws *a'* *b'* and fitted into the 95 grooves on the inner surfaces of the jaws, after which the conical expanding nut *D* is turned so as to cause the jaws to securely clamp and hold the wire.

From the above description of my invention 100 it will be seen that the device is of an extremely simple and inexpensive construction and permits the trolley-wire or the like to be securely clamped in place, the construction

also permitting the clamp to be readily opened, when desired, by simply unscrewing the nut D.

It will also be obvious from the above description that the invention is susceptible of some modification without material departure from its principles and spirit, and for this reason I do not wish to be understood as limiting myself to the precise form and arrangement of the device herein set forth.

Having thus described my invention, I claim—

1. In a wire-clamp, the combination of two pivotally-connected sections adapted to clamp the wire and means comprising a screw-threaded part connected to the sections and a wedging-block having screw-threads engaging with said screw-threaded part, said means being arranged for moving said sections into clamping engagement with the wire, substantially as set forth.

2. In a wire-clamp, the combination of two pivotally-connected sections adapted to clamp the wire, a screw-threaded wedging-block movable between the sections for forcing the sections into clamping engagement with the wire, and a screw-threaded part engaging the screw-threads of said wedging-block to move the same, substantially as set forth.

3. In a wire-clamp, the combination of two parts or sections to clamp the wire, a hinging-pin pivotally connecting the sections, a screw-threaded wedging-block movable between the parts or sections for forcing the same into

clamping engagement with the wire, and a screw engaging said wedging-block to move the same, substantially as set forth.

4. In a wire-clamp, the combination of two parts or sections pivotally connected and arranged to clamp the wire, a screw connected to the sections and an expanding nut screwing on the screw between the sections and provided with an integral conical portion arranged to engage the sections and force them into clamping engagement with the wire, substantially as set forth.

5. In a wire-clamp, the combination of two parts or sections pivotally connected and arranged to clamp the wire, a screw connected with the sections, and an expanding nut having a wedge-shaped portion arranged to engage the sections and force them into clamping engagement with the wire, said nut being provided with a passage in which are formed two sets of screw-threads, one to be engaged by the screw to move the nut relatively thereto when the nut is turned, and the other to be engaged by a supporting-bolt, substantially as set forth.

In witness whereof I have hereunto signed my name in the presence of two subscribing witnesses.

WILLIAM H. BRODIE.
